UNITED STATES PATENT OFFICE.

REUBEN C. ELDRIDGE, OF NIAGARA, CANADA.

SNAP-HOOK.

SPECIFICATION forming part of Letters Patent No. 582,780, dated May 18, 1897.

Application filed January 15, 1897. Serial No. 619,277. (No model.)

To all whom it may concern:

Be it known that I, REUBEN C. ELDRIDGE, a subject of the Queen of Great Britain, residing at Niagara Falls, in the county of Welland, in the Province of Ontario, Canada, have invented new and useful Improvements 5 in Snap-Hooks, of which the following is a specification.

This invention relates to snap-hooks which 10 are provided with a pair of hooks arranged at opposite ends of the body.

The object of my invention is the production 15 of such a double snap-hook which is comparatively short and slight in appearance and which permits the use of a single spring or tongue for both hooks, thus providing a spring of sufficient length to render it resili- 20 ent and durable.

In the accompanying drawings, Figure 1 is 25 a side elevation of my improved snap-hook. Fig. 2 is a longitudinal section thereof. Fig. 3 is an edge view of the hook.

Like letters of reference refer to like parts in the several figures.

25 The snap-hook is substantially S-shaped, and comprises a body or shank A and a pair of hooks B B, arranged at opposite ends of the body and facing in opposite directions. The body or shank and the two hooks are 30 cast or otherwise formed in one piece, and the body forms a common shank for both hooks and is arranged obliquely to the longitudinal center line of the hook.

35 C C' represent spring-tongues which respectively bear at their free ends against the noses of the snap-hooks, so as to close the mouths thereof in a well-known manner, and which are connected by an intermediate member C². These spring-tongues and the connecting member are preferably bent from a single piece, and form together a substantially S-shaped spring, as shown in the drawings. The central member C² of this spring and its bends c are seated in a longitudinal 45 slot or recess d, formed in the shank in the same plane as the hooks B.

ee represent transverse pins or rivets which are arranged in or intersect the slot d of the body near the ends thereof and around which 50 the bends c of the S-shaped spring extend, so

that said bends are loosely confined between the pins or rivets and the ends of said slot. These pins or rivets form abutments against which the tongues C C' of the spring are strained in depressing the same and around 55 which the bends of the spring are free to slide to a certain extent. The straining or deflection of either tongue is thus transmitted to the intermediate spring member C², and the resilience of the spring is thereby not only 60 increased, but the spring is rendered more durable. The S-shaped form, while providing a spring of sufficient length to insure the desired elasticity and durability, occupies at the same time a comparatively small space, 65 as the tongue of one hook lies against the back of the other, thus permitting the snap-hook to be made correspondingly shorter and lighter.

My improved snap-hook is especially desirable as a "bit-snap," but may also be used 70 for the various other purposes of ordinary snap-hooks.

I claim as my invention—

1. A double snap-hook, comprising a body 75 or shank, two oppositely-facing hooks arranged at opposite ends of said body or shank, and a single continuous spring composed of two outer branches or tongues bearing respectively against the noses of said hooks 80 and an intermediate member connecting said branches or tongues, substantially as set forth.

2. An S-shaped snap-hook comprising a body or shank having a longitudinal slot or 85 recess, two oppositely-facing hooks arranged at opposite ends of said body or shank, transverse pins or rivets arranged in said slot near opposite ends thereof and a continuous S-shaped spring seated in said slot and extending with its bends around said pins or rivets and bearing with its outer branches or tongues against the noses of said hooks, substantially 90 as set forth.

Witness my hand this 19th day of November, 1896. 95

REUBEN C. ELDRIDGE.
